UNITED STATES PATENT OFFICE.

EDWARD A. VERA, OF CHICAGO, ILLINOIS.

CHAUFFEUR'S IDENTIFICATION-TAG HOLDER.

Application filed August 8, 1921. Serial No. 490,602.

To all whom it may concern:

Be it known that I, EDWARD A. VERA, a citizen of the United States, residing at Chicago, in the county of Cook and State of Illinois, have invented certain new and useful Improvements in Chauffeurs' Identification-Tag Holders; and I do declare the following to be a full, clear, and exact description of the invention, such as will enable others skilled in the art to which it appertains to make and use the same.

My invention relates to improvements in holders for identification cards such as those used by chauffeurs and hackers, the object being to provide a novel tamper-proof device whereby the machine driven and the driver may be relatively identified whenever it should be advisable.

In addition to providing a holder of such form as to prevent the identification tag from being tampered with or changed in any manner, it is an object of the invention to provide novel means for mounting the holder upon an automobile, preferably upon one of the front fenders, although this location is not absolutely essential.

With the foregoing in view, the invention resides in the novel subject matter herein-after described and claimed, the descriptive matter being supplemented by the accompanying drawings.

Figure 1 is a perspective view showing the application of my invention to one of the front fenders of an automobile.

Figure 2 is an enlarged front elevation of the device partly in vertical section.

Figures 3 and 4 are respectively vertical and horizontal sectional views as indicated by the lines 3-3 and 4-4 respectively of Fig. 2.

Figure 5 is a perspective view of the cushioning sleeve which prevents all shocks and jars from being transmitted to the tag holding frame.

In the drawings above briefly described, the numerals 1 and 1^a designate the two halves of a frame which is adapted to carry an identification tag 2, displaying a photograph of the owner or driver of the vehicle, his name, license number, general description, etc., as indicated in Fig. 1. The frame 1-1^a is molded from glass and a pair of glass panels 3 and 3^a are formed integrally with said frame to cover the front and rear sides of the tag 2, the front panel 3 being provided with suitable protecting ribs, nipp-

les or the like 4 which prevent anyone from illegally pasting another identification tag on said panel. After the tag 2 has been inserted between the two panels 3 and 3^a, the frame sections 1 and 1^a are "frozen" or otherwise joined to each other in such a manner that they produce an integral structure which cannot be opened by unauthorized persons to permit the substitution of one identification card for another.

Integrally joined to the lower end of the frame 1-1^a and formed of two sections carrying the sections 1-1^a respectively, is a downwardly tapered plug 5 which is snugly received in a rubber sleeve 6, the outer side of this sleeve being preferably provided with vertical corrugations 7. The sleeve 6 is received in a suitable socket 8 having connection with any desired part of the vehicle. I prefer however to provide the lower end of the socket with an outstanding flange 9 which is riveted or otherwise secured to one fender of the machine, as shown in Fig. 1. The base of the socket member 8 is provided with a recess 10 into which the lower end of the plug 5 projects and a cotter pin or the like 11 passes through said plug end to secure the entire card holding device in the socket, a spring washer 12 being interposed between the pin and the top of the recess 10. By securing the device to the machine in the manner shown, the numerous shocks and jars incurred during travel of the machine, will not be injuriously transmitted to the glass frame and panels and consequently there is little danger of breakage. To additionally ward against breakage however, I preferably reinforce the frame and plug with a plurality of wires 13 as shown in Figs. 2, 3 and 4.

From the foregoing taken in connection with the accompanying drawing, it will be seen that I have provided a highly advantageous, tamper-proof identification cardholder, as well as a unique means for mounting it upon a vehicle. Since excellent results are obtainable from the details disclosed, they may well be followed, but it is to be understood that within the scope of the invention as claimed, numerous minor changes may be made.

I claim:

1. An identification device comprising an identification card, a pair of flat glass panels, contacting with the front and rear sides of said card respectively, glass frames integral

with and extending around said panels, said frames being integrally joined to each other, and a central attaching plug integral with the lower sides of said frames and extending 5 downwardly therefrom for reception in a socket.

2. An identification device comprising an identification card, a pair of flat glass panels, contacting with the front and rear sides of 10 said card respectively, glass frames integral with and extending around said panels, said frames being integrally joined to each other, an attaching plug integral with and extending downward from the lower sides of said 15 frames, and re-inforcing wires having their ends embedded in said attaching plug, the intermediate portions of said wires extending through and being embedded in the sides of said frames.

20 3. The combination with a glass identifica-

tion device having an integral downwardly tapered plug, of an elastic sleeve snugly surrounding said plug and having vertical ribs closely spaced around its outer side, a tapered socket in which said sleeve and plug 25 are snugly received with said ribs in contact with the wall of the socket and means for yieldably holding said plug in said socket.

4. An identification device comprising a glass body having a transparent panel and 30 an integral frame around the same, and an identification card within said body visible through said panel, the outer side of said panel having integral means projecting therefrom to prevent pasting of a fictitious 35 card thereon within the frame.

In testimony whereof I have hereunto set my hand.

EDWARD A. VERA.
